REMOTE CONTROL OF RADIO APPARATUS

Rudolf Weber, Berlin, Germany, assignor to
 Telefunken Gesellschaft fur Drahtlose Tele-
 graphie m. b. H., Berlin, Germany, a corpora-
 tion of Germany

Application October 25, 1935, Serial No. 46,735
 In Germany October 1, 1934

5 Claims. (Cl. 172—239)

This invention relates to a remote control sys-
 tem in which each definite displacement of the
 control knob at the place of control causes a
 corresponding displacement of the remotely con-
 trolled organ.

5 The present invention relates to a remote con-
 trol whereby each displacement of the control
 knob at the place of control (for instance a ro-
 tational displacement) causes a corresponding
 10 displacement of the respective organ at the re-
 motely controlled place (for instance likewise a
 rotational displacement).

The remote control arrangement according to
 this invention is as follows:

15 At the transmitter side there is coordinated
 with each position of the control knob of the
 place of control in an unequivocal manner a defi-
 nite value of a variable frequency f and there is
 coordinated with each of the two directions of
 20 movement of the control knob one of two con-
 stant frequencies f_1 or f_2 respectively. At the re-
 ceiver side the respectively received fixed fre-
 quency f_1 or f_2 releases a movement of the driving
 25 motor in the one or in the other direction,
 respectively, and which displaces the organ to be
 remotely controlled in the desired direction for
 such length of time, thereby also varying the tun-
 ing of an oscillatory circuit fed by the receiver
 30 (resonator) of the variable frequency f for such
 length of time until the said oscillatory circuit
 is in resonance with the frequency f by which it
 is excited, thereby causing the shutting off of
 the driving motor whereby the remotely con-
 trolled organ comes to a stand still.

35 An example of an embodiment of the idea of
 the invention is schematically represented in the
 drawing in which Fig. 1 is a diagram of a trans-
 mitter arrangement, and Fig. 2 is a diagram of a
 receiver arrangement.

40 The transmitter, see Figure 1, contains an os-
 cillator 1 for producing a constant frequency f_1 ,
 a further oscillator 2 for another constant fre-
 quency f_2 and an oscillator 3 for a variable fre-
 quency f . The frequency energies respectively
 45 derived from their outputs 1', 2', and 3' are pref-
 erably amplified by a suitable known amplifier ar-
 rangement not shown in detail herein, and are
 employed for modulating a transmitter (likewise
 not shown herein). In displacing a control or-
 50 gan, for instance, by turning a hand wheel 5 the
 frequency f will be increased or decreased in ac-
 cordance with the direction in which the control
 organ is moved. Furthermore, for each position
 of the control range and in accordance with di-
 55 rection of turning of the hand wheel the contact

A or B of the switch 4 will be closed so that, for
 instance, in turning the wheel towards the left,
 the oscillator 1 will be connected, while by turn-
 ing the wheel in the opposite direction, the oscil-
 lator 2 will be connected (while oscillator 1 is si-
 multaneously disconnected).

The receiver arrangement, see Figure 2, con-
 tains resonators 6 and 7 for the fixed frequencies
 f_1 and f_2 respectively, and the resonator for the
 variable frequency f . The resonators are pref-
 erably excited at their inputs 6', 7' and 8' by
 10 the usual receiver apparatus (not shown in de-
 tail on the drawing) and they in turn excite re-
 lays of suitable and known constructions which
 may be direct current amplifying relays or res-
 onance relays. These relays have not been shown
 15 in connection with the resonators 6 and 7 and are
 assumed as being included in the apparatus 6 and
 7. The resonator 8 is so coupled with a displace-
 ment motor 9 that in accordance with the direc-
 20 tion of rotation of the motor, an increase or de-
 crease of the natural resonance takes place.
 Both of the resonators 6 and 7, respectively,
 switch in the motor current through the respec-
 25 tive frequency f_1 or f_2 and in such manner that
 the one resonator causes the current to pass
 through the motor in the one direction, while the
 other resonator passes the current in the other
 30 direction thereby causing the motor to rotate in
 the corresponding direction of rotation. This
 control of the motor is indicated in the drawing
 in a purely schematical manner by the signs $\pm$
 and $\mp$ at the places 11 and 12, respectively. An
 35 interrupter relay 10 is furthermore placed in the
 motor current circuit and which is released by
 the resonator 8.

The functioning of the arrangement is as
 follows:

40 At the transmitter the turning of the hand
 wheel 5 towards the left, for instance, closes the
 contact A and therefore sets the oscillator 1 in
 operation. Furthermore, the variable frequency f
 will be decreased at a certain amount correspon-
 45 ding with the turning of the hand wheel. At the
 receiver, the resonator 6 responds to the fre-
 quency f_1 and releases a current which causes
 the displacement motor 9 to rotate in a certain
 direction. At the same time, the resonance po-
 50 sition of the resonator 8 will thereby be dis-
 placed and finally attains the frequency f radi-
 ated by the transmitter. The interrupter relay
 10 is thereby put in operation and interrupts the
 circuit of the motor.

55 A rotating movement in the opposite direction
 at the transmitter would result in the production

of the frequency f_2 and in an increase of the oscillator frequency f . At the receiver the resonator 7 would respond and the displacement motor 8 would thereby be caused to rotate in the opposite direction so that also in this case the resonator 8 would finally attain the frequency f and interrupt the motor current across the interrupter relay. The described system for remote control is suited with particular advantage to the transmission of wireless control signals but it can also be used for the transmission across wire lines.

Having thus described my invention, what I claim is:

15. Remote control apparatus for producing a definite displacement to a remotely located controlled organ, from an organ located at the place of control comprising a transmitter having control means which is coordinated to each position 20 of the control means at the place of control with an unequivocal and definite value of a variable frequency, said control organ arranged to have two directions of movement each of which corresponds to a first and second constant frequency, 25 a first and second oscillator for producing said frequencies, a receiver having means whereby said first and second constant frequency releases a movement of a displacement motor in the one or other direction, said motor displacing the organ 30 to be remotely controlled in the desired direction during such length of time, and at the same time, thereby varying the tuning of an oscillatory circuit excited by the receiver of the variable frequency during such length of time until the said 35 oscillatory circuit is in resonance with the variable frequency by which it is excited thereby causing energization of a relay for shutting off of the displacement motor and bringing the remotely controlled organ to a standstill.
40. Remote control apparatus for producing a definite displacement to a remotely located controlled organ from an organ located at the place of control comprising a transmitter having a control device with manual means for increasing or 45 decreasing the value of a variable frequency of an oscillator, a first and second fixed oscillator connected to said first mentioned control organ, means associated with said first mentioned control organ whereby said first fixed oscillator is 50 made operative when the value of said variable oscillator is decreased and said second oscillator is made operative when the value of said variable oscillator is increased, a receiver having means responsive to said first and second fixed oscillators, a motor coupled to said means responsive to said first and second fixed oscillators, the direction of said motor being controlled by current received by said first and second frequencies, and means for connecting said 55 remotely controlled organ with said motor whereby current from said variable frequency energizes said resonant relay to cause said motor to become inoperative.
55. Remote control apparatus for producing a definite displacement to a remotely located controlled organ from an organ located at the place of control comprising a transmitter having a control device with manual means for increasing or 60 decreasing the value of a variable frequency of an oscillator, a first and second fixed oscillator connected to said first mentioned controlled organ, means associated with said first mentioned controlled organ whereby said first fixed oscillator is made operative when the value of said variable oscillator is decreased and said second oscillator is made operative when the value of said 65 variable oscillator is increased, a receiver and a resonant relay having means responsive to said first and second fixed oscillators, a motor coupled to said means responsive to said first and second fixed oscillators, the direction of said motor being controlled by current received by said first and second frequency, and a relay having control means for connecting said 70 remotely controlled organ with said motor whereby current from said variable frequency energizes said resonant relay to cause said motor to become inoperative.
65. Remote control apparatus for producing a definite displacement to a remotely located controlled organ from an organ located at the place of control comprising a transmitter having a control device with manual means for increasing or 75 decreasing the value of a variable frequency of

an oscillator, electrical contacts associated with said manual device, a first and second fixed oscillator connected to said first mentioned control organ, means associated with said first mentioned controlled organ whereby said first fixed oscillator is made operative when the value of said variable oscillator is decreased, and said second oscillator is made operative when the value of said variable oscillator is increased, a receiver having means responsive to said first and second fixed oscillators, a motor coupled to said means responsive to said first and second fixed oscillators, the direction of current controlled by current received by said first and second frequencies, and means for connecting said 100 remotely controlled organ with said motor whereby current from said variable frequency energizes a relay to cause said motor to become inoperative.

4. Remote control apparatus for producing a definite displacement to a remotely located controlled organ from an organ located at the place of control comprising a transmitter having a control device with manual means for increasing or decreasing the value of a variable frequency of an oscillator, a first and second fixed oscillator connected to said first mentioned controlled organ, means associated with said first mentioned controlled organ whereby said first fixed oscillator is made operative when the value of said variable oscillator is decreased, and said second oscillator is made operative when the value of said variable oscillator is increased, a receiver and a resonant relay having means responsive to said first and second fixed oscillators, a motor coupled to said means responsive to said first and second fixed oscillators, the direction of said motor being controlled by current received by said first and second frequencies, and means for connecting said 150 remotely controlled organ with said motor whereby current from said variable frequency energizes said resonant relay to cause said motor to become inoperative.

5. Remote control apparatus for producing a definite displacement to a remotely located controlled organ from an organ located at the place of control comprising a transmitter having a control device with manual means for increasing or decreasing the value of a variable frequency of an oscillator, a first and second fixed oscillator connected to said first mentioned controlled organ, means associated with said first mentioned controlled organ whereby said first fixed oscillator is made operative when the value of said variable oscillator is decreased and said second oscillator is made operative when the value of said variable oscillator is increased, a receiver and a resonant relay having means responsive to said first and second fixed oscillators, a motor coupled to said means responsive to said first and second fixed oscillators, the direction of which is controlled by current received by said first and second frequency, and a relay having control means for connecting said 200 remotely controlled organ with said motor whereby current from said variable frequency energizes said resonant relay to cause said motor to become inoperative.

RUDOLF WEBER.
